United States Patent Office.

JACOB WALDRON, OF NORTH CREEK, NEW YORK.

Letters Patent No. 92,675, dated July 13, 1869.

IMPROVED MILK-SAFE.

The Schedule referred to in these Letters Patent and making part of the same.

To all whom it may concern:

Be it known that I, JACOB WALDRON, of North Creek, in the county of Warren, and in the State of New York, have invented certain new and useful Improvements in Milk-Safes; and do hereby declare that the following is a full, clear, and exact description thereof, reference being had to the accompanying drawings, and to the letters of reference marked thereon, making a part of this specification.

The nature of my invention consists in the construction and arrangement of a revolving safe for keeping milk, butter, cheese, or other articles, cool and out of the way from flies, bugs, or other animals.

In order to enable others skilled in the art to which my invention appertains, to make and use the same, I will now proceed to describe its construction and operation, referring to the annexed drawings, in which—

Figure 1 is a horizontal section, and

Figure 2 is a side elevation of my safe.

A represents a vertical shaft or beam, of suitable dimensions, having a pivot, *a*, at each end, so that it may be placed in suitable pivot-boxes, and revolved at pleasure.

Near the upper end of the shaft A, and on the same, is secured a horizontal top, B, of octagon shape, and to each corner of said top, is secured a vertical strip, *b*, which extends downward.

The lower ends of the vertical strips *b* are connected by horizontal strips *c*, forming an octagon frame, a trifle less in diameter than the octagon top B.

In the octagon frame *c* are placed shelves or lattice-work, *d*, of the peculiar arrangement shown in fig. 1, the shelves crossing each other, forming shelving room for twelve pans, there being three opposite every other side of the frame *c*.

The shelves *d* are secured or fastened by screws to the lower ends of the strips *b*, or they may be made secure to the frame *c*, in either case also serving as braces for the machine.

Between this shelving and the top B is placed a series of similar shelves at regular distances apart, and secured by screws to the strips *b*. In a full-sized safe I intend to place eight such intermediate rows of shelving, making room for one hundred and eight pans.

From near the lower end of the shaft A, four braces, C C, extend upward and outward, the upper ends of

said braces being under the point where the shelves *d* cross each other. At this point, between each row of shelving, is placed a wooden tube, *e*, forming supports for the shelves.

Through the upper ends of the braces C C, through the shelves *d*, and tubes *e*, are passed rods *i*, which also pass through the top B, and are secured by nuts, thus holding the whole safe firmly together.

Under the lowest shelving is stretched fine wire webbing or netting, which is secured to the under side of the frame *c*.

Every other side of the safe, namely, the sides where each row of shelving forms room for three pans, as above mentioned, is provided with a door, *f*. The doors *f*, and the remaining four sides of the safe, are also covered with fine wire webbing, preventing flies or bugs from coming into the milk.

The safe, thus constructed, is placed in a cellar or milk-room, so that it can be revolved with ease. One of the doors, *f*, is opened, and the shelving on this side filled with pans of milk, when the door is closed, the safe turned one-fourth around, and that side filled, and so on until all the milk is put away.

It will, of course, be understood that this safe can be used for cheese, or any other articles that it may be desired to put away for a certain length of time. The wire webbing, at the same time that it prevents flies or other bugs from coming in the milk, allows free circulation of air, so as to cool or keep cool the articles placed therein.

My safe can be easily taken apart, and put up again, and saves a great deal of room.

Having thus fully described my invention,

What I claim as new, and desire to secure by Letters Patent, is—

The arrangement of the octagon frame B *b* *c*, with wire screen on sides and bottom, a series of shelving *d*, supporting tubes *e*; and rods *i*, with the braces C C, and pivoted shaft A, all as shown and described.

In testimony that I claim the foregoing, I have hereunto set my hand, this 29th day of April, 1869.

JACOB WALDRON.
